UNITED STATES PATENT OFFICE.

CHARLES V. ROTE, OF LANCASTER, PENNSYLVANIA, ASSIGNOR OF ONE-HALF TO E. W. BROWN, OF LANCASTER, PENNSYLVANIA.

PULL MECHANISM FOR RAILWAY CARS.

Application filed September 19, 1921. Serial No. 501,635.

To all whom it may concern:

Be it known that I, CHARLES V. ROTE, a citizen of the United States, residing at Lancaster, in the county of Lancaster and 5 State of Pennsylvania, have invented new and useful Improvements in Pull Mechanism for Railway Cars, of which the following is a specification.

The present invention relates to improvements in pull mechanism for railway cars, and has among its objects to provide means by which a train of cars may be started more smoothly and with less jar than can be done with the draft devices commonly employed. 10 15 A further object of the invention is to provide a pull mechanism by which the springs of the ordinary draft connection to the couplers will be relieved from the initial strain incident to starting a train; and 20 by which danger of a coupling being detached from a car will be reduced to a minimum.

According to the present invention the draft or pull exerted on a coupling is immediately transferred to the forward coupling of the next car to the rear so that the last car in a train will be started before any of the cars in advance thereof.

In the accompanying drawings:— 30 Figure 1 is a plan of the frame-work of a railway car having an embodiment of the invention applied thereto.

Figure 2 is a side elevation.

Figures 3 and 4 are plan views of the improved pull mechanism detached from the car and, respectively, showing the positions of the several elements before and after a pull is exerted thereon.

Figure 5 is a vertical section of the parts 40 shown in Figures 1 and 2.

Figure 6 is a more or less diagrammatic plan of two cars, each provided with an embodiment of the present invention, showing the parts in the positions occupied at the 45 commencement of pull thereon.

Figure 7 is a similar view illustrating the position assumed when a pull has been exerted on the forward coupler.

Referring to the drawings, the car frame 50 illustrated comprises a central, longitudinal, box-like sill or girder 1 having vertical webs and transverse sills 2 extending laterally from said central sill. The frame is supported on suitable trucks extending beneath 55 the transverse sills 2.

As the invention can manifestly be applied to car frames of various forms, it is not deemed necessary to illustrate more in detail any particular frame.

3, 3', designate the draft couplers arranged 60 at opposite ends of the longitudinal sill 1, and between said sill and the draw bar of each coupler is arranged a suitable draft gear. As illustrated, this comprises a coil spring 4, the opposite ends of which bear 65 against the plates 5, 6, that, respectively, cooperate with abutments 7, 8, on the sill 1.

Two bell crank levers 9, 10, are pivotally connected to stationary abutments or lugs projecting from opposite sides of the sill 1, 70 adjacent the coupler 3, similar levers 9', 10', being pivotally connected to the frame adjacent the other coupler 3'. As shown, the pivotal connections or fulcrums for said bell cranks are arranged in the projecting ends 75 of bars 11, 11', that extend transversely through the box-like sill 1 and project beyond the opposite sides thereof. It will be evident, however, that the bell cranks might be fulcrumed on lugs projecting from the 80 sides of the sill, the only essential being that such fulcrums are relatively stationary, that is, not adapted to move longitudinally of the girder 1 when force is applied to the bell cranks.

Each bell crank constitutes one member of a toggle, the other member 12, 12', of which has its ends pivotally connected to the bell crank and to a bar 13, 13', that extends transversely of the sill 1 and projects 90 beyond the sides thereof. The projecting ends of the bars 13, 13', are rigidly connected by links 14, and said bars are each adapted to move longitudinally of the sill 1, the latter being provided with slots 15, 95 15', through which said bars extend.

The outwardly projecting arms of the bell cranks are each connected through rods 16 with the adjacent coupler head 3, 3', and it will be seen that when a pull is exerted on 100 either of said heads the connected bell cranks will be rocked and caused to expand the toggles directly connected therewith while effecting a corresponding contracting or closing movement of the other toggles.

In Figures 1, 3 and 6, the parts are shown in the positions occupied prior to starting to pull a train in a left hand direction. It will be seen that in this position the toggles on opposite sides of the sill 1 adjacent 105 110

the coupler 3 are in contracted or closed position, whereas the other toggles connected directly to the coupler 3' are in open or expanded position. Pull on the coupler 3 will 5 rock the bell cranks 9, 10, about their pivotal connections to the car frame and effect a bodily movement of the transverse bars 13, 13', to the left in the slots 15, 15'. This movement will cause an expansion of the 10 toggles adjacent the coupler 3 and a contraction of the other toggles which are connected to the draw head 3' and the pull exerted on this last coupler by the turning movement of the bell cranks 9', 10', will be 15 exerted directly on the forward coupler of the next car to the rear. This adjustment or varying of the relation of the several parts will be duplicated on every car in rear of the one to which draft is initially applied, 20 with the result that the last car in the train will be started first.

As previously stated, the draft gear between each coupler and the sill 1 may be of the ordinary type. When originally constructed the parts of such mechanism are 25 so related that the follow plates 5, 6, are normally held by the spring or springs in contact with the abutments 7, 8, on the car. After a relatively short period of use, however, the springs cease to maintain close contact between such abutments and plates or considerable "slack" is produced. As the 30 present invention does not depend upon maintaining close contact between the plates 35 5, 6, and abutments, but is adapted to take up all of the "slack" that may have been produced by use, the plates are shown as separated or spaced from such abutments.

In other words, as applicant's invention 40 is not dependent upon actual normal contact between the plates 5, 6, and car abutments, these parts have been shown as separated in the drawings. The operation of the parts of the present invention will 45 not be hampered or interfered with if the plates 5, 6, of the friction draft gear are in contact with the car abutments, but it has been thought best to illustrate these 50 parts as separated to show clearly that the action of applicant's pull mechanism is independent thereof.

According to the present invention, the 55 springs 4 are only necessary in checking "buffing" movements of the cars.

The improved pull mechanism may be 60 readily applied to cars that have been in use for a considerable period of time, so that a maximum amount of "slack" has been produced in the draft gear or in new constructions such gear may be so proportioned that there is no normal contact between the plates 5, 6 and abutments 7, 8.

It will be seen that by the construction 65 illustrated and described in which a toggle is interposed between each coupler and the

longitudinally movable bars 13, 13', there is provided a draft rigging, the effective length of which is variable, and the results of this arrangement of parts is, as above stated, that in actual use the last car of a train will 70 be started before the cars in advance thereof.

In addition to furnishing a connection between the coupler and bell cranks, it will be seen that the rods 16 serve as a means for supporting the couplers from the car frame. 75

As commonly mounted, the couplers are supported solely by the draw bars, and it frequently happens that this connection is broken, causing the coupler to fall and frequently effecting de-railment of the car. The 80 rods 16, however, extending as they do through the sill 1 at opposite sides of the draw bar, provide an additional support or connection for the coupler and materially strengthen this portion of the mechanism. 85

It is thought that the operation and advantages of the improvements will be readily understood from the foregoing description in connection with the drawings.

As shown diagrammatically in Figs. 6 and 90 7, and also in Figs. 3 and 4, the parts are so arranged that prior to a pull in either direction the forward toggles are contracted, while the rear toggles of each car may be expanded. The parts are brought to this 95 position by the engineer moving the locomotive to properly adjust the cars by "bunching" them, and when a forward pull is exerted on the coupler 3 this movement through the link and toggle connections is immediately transferred to the rear car of the train 100 so that the cars in advance are started without any sudden pull or jerk, which, under ordinary constructions, is so detrimental to the parts of the draft rigging. The invention 105 provides a positive and direct connection between all of the cars of the train and relieves the spring of the ordinary friction draft gear from the strains to which it is commonly subjected. 110

Having thus described the invention, what is claimed as new is:

1. The combination with a railway car frame, having a draft coupler at each end, of two toggles each having both members pivotally connected to the car frame, the connection between one of said members and the frame being movable in the direction of the length of the frame and the connection of the other member to the 115 frame being fixed, a rigid connection between the said movable members of the toggles, and a connection between each toggle and the adjacent coupler. 120

2. The combination with a railway car 125 frame having a draft coupler at each end, of two toggles each having the outer end of one arm pivotally connected to a stationary part of the car frame, means connecting the other arms of the toggles and bodily 130

movable longitudinally of the car frame, and a connection between each toggle and the adjacent coupler.

3. The combination with a railway car frame having a draft coupler at each end, of two bell crank levers each having one arm pivotally connected to a stationary part of the car frame, a link pivotally connected at one end to each bell crank and forming therewith a toggle, a rigid connection between the other ends of said links movable longitudinally of the car frame, and a connection between the other arm of each bell crank and the adjacent coupler.

10 4. The combination with a railway car frame having a draft coupler at each end, of two bell crank levers each having one arm pivotally connected to a stationary part of the car frame, a link pivotally connected at one end to each bell crank and forming therewith a toggle, a rigid connection between the other ends of said links including a member extending through a slot in the car frame and movable longitudinally thereof, and a connection between the other arm of each bell crank lever and the adjacent coupler.

5. The combination with a railway car frame having a draft coupler at each end and a central longitudinal sill, of toggles arranged on both sides of the sill, each having one member pivotally connected to the sill by relatively stationary pivots, links connecting the other members of the toggles on each side of the sill, a connection between said links extending transversely of the sill and movable longitudinally thereof, and rods extending from each coupler to the adjacent toggles on both sides of the sill.

40 6. The combination with a railway car frame having a draft coupler at each end and a central longitudinal sill, of bell cranks on both sides of the sill adjacent each coupler, one arm of each bell crank being pivoted to a stationary portion of the sill, a link pivotally connected to each bell crank and forming therewith a toggle, means connecting said links and engaged with the sill to move longitudinally thereof, and rods connecting each coupler with the other arms of the adjacent bell cranks on both sides of the sill.

7. The combination with a car frame having a draft coupler at each end and a central longitudinal sill, of a bar extending transversely of the sill and movable longitudinally thereof, two toggles on each side of the sill between said bar and the ends of the car, each of said toggles having one member connected to said bar and its other member connected to a stationary projection on the sill, and connections between each coupler and both of the adjacent toggles

65 8. The combination with a car frame having a draft coupler at each end and a central longitudinal sill provided with longitudinal slots that open through its sides, a bar extending transversely through said slots and movable longitudinally therein, two toggles on each side of the sill between said bar and the ends of the car, each of said toggles having one member connected to a stationary projection on the sill, and connections between each coupler and the adjacent toggles on both sides of the sill.

9. The combination with a railway car frame having a draft coupler at each end and a central longitudinal sill provided with two transverse slots, a bar extending transversely of the sill through each of said slots and movable longitudinally of the sill, a rigid connection between said bars, two toggles on each side of the sill each having one member connected to one of said bars and its other member connected to a stationary part of the sill, and connections between each coupler and both of the adjacent toggles.

90 10. The combination with a railway car frame having a draft coupler at each end and a central longitudinal sill provided with two transverse slots, a bar extending transversely of the sill through each of said slots and movable longitudinally of the sill, a rigid connection between said bars, four bell cranks each pivotally connected to a stationary part of the sill between said bars and the ends of the frame, a link connecting each bell crank with one of said bars, and rods connecting each coupler with the other arms of both adjacent bell cranks.

In testimony whereof I have hereunto set my hand.

CHARLES V. ROTE.
